UNITED STATES PATENT OFFICE

SAMUEL ORKIN, OF BEVERLY HILLS, CALIFORNIA, ASSIGNOR TO CALWIS INDUSTRIES, LTD., OF BEVERLY HILLS, CALIFORNIA, A CORPORATION OF CALIFORNIA

STOP DEVICE FOR TOY MOTORS

Application filed February 10, 1932. Serial No. 592,029.

My invention relates to toy motor constructions, and has particular reference to a stop device for controlling the starting and stopping of a spring motor.

5 In my copending application, Serial No. 570,056, filed October 21, 1931, I disclosed a spring motor for driving toys, in which the power of a relatively heavy spring was applied through reduction gearing through a power take-off device adaptable to operate toy boats, and other mechanically driven toys.

10 The present invention relates to a new and novel stopping device in the form of a brake which may be applied to the power take-off.

15 In the art of toy motors, it has been the practice to apply a stopping device to such motors in one or the other of two ways, namely, to engage a substantially rigid bar with a part of the power take-off device or with some of the intermediate gearing, or to apply a spring tensioned friction brake to some part of the moving apparatus. The 20 first of these constructions is objectionable, however, due to the positive engagement of the bar with the moving parts of the apparatus causing severe shock to the same and creating an objectionable noise, while the latter arrangement requires the employment of springs and necessarily complicated constructions for applying and relieving the pressure.

25 It is, therefore, an object of this invention to provide a stop device for small motors in which the brake application is made in a positive manner but in which the engagement of the brake device is made through a spring tension.

30 Another object of the invention is to provide a brake device as set forth in the preceding paragraph in which the brake is applied to some smooth part of the moving apparatus so that objectionable shocks are not created.

35 Other objects and advantages will be apparent from a study of the accompanying drawing, read in connection with the following specifications, wherein

40 Figure 1 is a side elevational view of a toy motor provided with a brake constructed in accordance with my invention;

45 Figure 2 is a detail, top plan view of the brake shown in Figure 1;

50 Figure 3 is a detail, sectional view, taken along line III—III of Figure 1; and

55 Figure 4 is a detail sectional view taken along line IV—IV of Figure 2.

60 Referring to the drawing, I have illustrated therein a toy motor construction in which a power take-off device 1 is fixed upon a suitable shaft 2 mounted in bearings 3 and 4 upon an assembly plate 5. The shaft 2 is arranged to be driven through the agency of a beveled gear 6 which is engaged by a second beveled gear 7 mounted for rotation between the assembly plate 5 and a top plate 8.

65 The gear 7 is illustrated as being driven through the agency of suitable reduction gearing 9 mounted between the plates 5 and 8 and in turn connected through a driving gear 10 to be driven by a power supply spring 11. The spring 11 is shown as being mounted in a space between the assembly plate 5 and a base plate 12.

70 As was described in my copending application, described above, the bearing members for the power take-off device are comprised by means of a downwardly struck lug from the plate 5, constituting the bearing member 3, while the end of the plate 5 is bent downwardly to constitute one-half of the bearing member 4. The bearing member 4 is completed by means of a plate 13 riveted thereto as at 14, the plate 13 having a slot extending vertically from its top surface, while the down-turned end of the plate 5 is provided with a slot extending from its lower surface so that the assemblage of the two members 4 and 13 constitute a circular bearing 75 in which the shaft 2 may operate.

80 The power take-off device 1 is illustrated as providing a composite structure including a grooved pulley 15, a spur gear 16 and a brake structure 17 formed integrally with each other, the rear surface of the brake surface 17 being provided with a pair of rearwardly extending lugs 18 which may be employed as in the construction described in my copending application for the purpose of engaging a brake device. However, in the 85 embodiment of the invention shown herein,

I prefer to employ a smooth cylindrical surface 19 formed upon the brake device 17 immediately at the rear of the gear 16 and to engage this surface by a brake shoe 20 in such manner that a smooth braking contact is employed between the surface 19 and the shoe 20.

By referring particularly to Figure 1, it will be observed that a brake mounting plate 21 is provided secured to the top plate 8, as by means of screws 22. The brake mounting 21 extends longitudinally of the plate 8 and has formed thereon a plurality of downwardly struck lugs 23 and 23' spaced from each other to constitute a slideway for a brake operating rod or bar 24. At intervals along the length of the mounting member 21, I have provided upstanding lugs or ears 25 each of which is provided with an opening 26 therethrough to receive a pivot pin 27 for mounting a brake operating lever 28. The purpose of providing a plurality of the ears 25 is to permit the brake operating lever to be mounted at any one of a number of points along the length of the motor most convenient to the particular toy or device to which my motor may be attached.

The brake operating lever 28 is illustrated as having at its lower end a bifurcated arm 29 arranged to surround and engage the outstanding stud 30 formed upon the brake operating rod 24, it being understood that there will be a plurality of the studs 30 provided along the length of the rod 24 for the purpose of engaging the arm 29 when the lever 28 is mounted in any one of its plurality of positions.

By referring particularly to Figure 2, it will be observed that the extreme left-hand end of the brake operating rod 24 is turned inwardly, as at 31, to terminate substantially in alignment with the axis of rotation of the shaft 2. The brake shoe 20 is illustrated as being formed of a length of strap material, preferably formed of resilient material, one end 32 of which is illustrated as being bent downwardly and secured to the inturned end 31 of the rod 24, as at 33. The other end of the shoe 20 is illustrated as being bent downwardly and rearwardly upon itself to present an angular engaging surface to the brake device 17 so that rearward movement of the brake operating rod 24 will move the brake shoe out of effective engagement with the brake device 17, while movement of the rod in the opposite direction will cause the brake shoe to engage the brake device with increasing pressure, dependent upon the amount of movement given the rod 24.

The bearing plate 13 is illustrated as extending considerably above the axis of the shoe 2 and is provided near its upper end with an outwardly struck lug 34 immediately adjacent the upper surface of the brake shoe 20 so that this lug 34 constitutes a bearing against which the force of the contact of the

brake shoe against the brake device may be received, thus insuring against distortion of the brake shoe 20, and further insuring that adequate pressure will be brought to bear upon the brake device 17. The opening 70 formed by the striking up of the lug 34 constitutes an opening in the plate 13 through which the brake shoe projects, thus providing in a single assembly a guide for the brake shoe and a reaction support for the brake 75 application.

The operation of the braking device is as follows: By manipulating the lever 28 to move the rod 24 to the right, the shoe 20 is withdrawn from the brake surface 19, permitting the spring 11 to effectively rotate the shaft 2, and the power take-off device, while operation of the brake lever 28 in the opposite direction will cause the brake shoe to be projected to the left, as shown in the drawing, and thus engage the surface 19. The initial contact between the brake shoe 20 and the surface 19 will be slight, due to the angularity of the brake shoe 20, while further movement of the rod 24 will increase the pressure of contact between these members and will exert a sufficient friction retarding force to bring the power take-off device to rest. However, during the entire application of the brake, there is no possibility of engagement 95 between any outstanding part of the power take-off device and the brake shoe so that the entire application of the brake is one of applying smooth contact surfaces to each other and hence no shock is produced by the 100 application of the brake.

While I have shown and described the preferred embodiment of my invention, it is to be understood that I do not desire to be limited to any of the details of construction shown or described herein, except as defined in the appended claims.

I claim:

1. In a brake device for toy motors having a power take-off device, a brake operating rod, means mounting said rod for movement parallel to the axis of rotation of said power take-off device, a brake surface formed upon said power take-off device, and a brake shoe formed of a strip of resilient material secured to said brake operating rod and movable therewith into engagement with said braking surface.

2. In a brake device for toy motors having a power take-off device, a bearing plate for mounting said power take-off device for rotation, a brake operating rod, means mounting said rod for movement in a direction parallel to the axis of rotation of said power take-off device, a brake engaging surface on said power take-off device, an opening in said bearing plate, a brake shoe formed of a strip of resilient material secured to said brake operating rod and projectable through 130

said opening in said plate to engage said braking surface.

3. In a brake device for toy motors having a power take-off device, a brake operating rod, means mounting said rod for movement parallel to the axis of rotation of said power take-off device, a brake surface formed upon said power take-off device and a brake shoe secured to said brake operating rod and 5 formed of a strip of resilient material having a portion thereof extending parallel to the axis of rotation of said take-off device, and having a portion thereof bent back upon itself to form an acute angle with said first- 10 named portion.

4. In a brake device for toy motors having a power take-off device, a bearing plate for mounting said power take-off device for rotation, a brake operating rod, means mounting 20 said rod for movement in a direction parallel to the axis of rotation of said power take-off device, a brake engaging surface on said power take-off device, a lug struck from said bearing plate and extending toward said 25 power take-off device, and a brake shoe formed of a strip of resilient material secured to said brake operating rod and projectable through the opening left by said upstruck lug and bearing against said lug to engage 30 said brake and surface whereby the reactive force of said brake pressure is borne against said lug.

Signed at Los Angeles, California, the 2nd day of February, 1932.

35 SAMUEL ORKIN.
